UNITED STATES PATENT OFFICE.

EMIL SCHAUFFELBERGER, OF PUTNEY, LONDON, ENGLAND.

APPARATUS FOR THE MANUFACTURE OF CELLULOSE.

1,282,635.

Specification of Letters Patent. Patented Oct. 22, 1918.

Application filed May 25, 1917. Serial No. 170,982.

To all whom it may concern:

Be it known that I, EMIL SCHAUFFELBERGER, a citizen of the Swiss Republic, and residing at 119 Kenilworth Court, Putney, 5 London, S. W., England, have invented certain new and useful Improvements in the Apparatus for the Manufacture of Cellulose, of which the following is a specification.

This invention relates to the manufacture 10 of cellulose, and while it is particularly suitable for the process of treatment or preparation which consists in digesting bamboo, esparto, wood pulp or other suitable fibrous material by means of heated liquor (and by 15 liquor is meant any liquid, whether acid or alkaline, which may be used for this purpose) in a digester, it is also suitable for similar operations in which a material is to be extracted from a fibrous base by a process 20 of indirect cooking or digesting.

In such processes as hitherto carried out great difficulties have been experienced due to the fact that no adequate means have been provided for preventing the clogging and 25 encrustation of the pumping and heating devices employed by fibrous matter and by scum or other impurities carried by the circulating liquor. Attempts have been made to overcome these difficulties by providing a 30 form of apparatus in which the liquor is circulated through the digester in a downward direction, while the digester is fitted with an internal strainer situated near the lower part of the digester for the purpose of retaining 35 the fibrous matter within the digester and preventing chips from being drawn into the pumping and heating devices. This arrangement, however, suffers from the disadvantage that the internal strainer is under 40 considerable pressure due to the superincumbent head of pulp and such pressure as may be necessary to force the liquid through the pulp column, the result being that the pulp in the immediate vicinity of the strainer is 45 broken up under such pressure and is forced through the apertures in the strainer so that the difficulties above noted are not in any way obviated and, moreover, the product produced is not in any way separated from 50 the scum or other impurities that commonly float in or on the liquor, with the result that serious difficulties are encountered in the later processes of treatment.

The object of the present invention is to provide improvements in the carrying out 55 of such operations as will remove the above difficulties and disadvantages, and according to my invention I interpose in the system means such that the scum or other impurities carried by the liquor will be separated 60 therefrom before the liquor passes to the heating and pumping devices forming part of the system.

The invention also comprises other details 65 and arrangements hereinafter described or indicated.

The accompanying drawings illustrate 70 more or less diagrammatically one convenient form of apparatus for carrying out the invention.

In carrying my invention into effect in one convenient manner when applying it, for example, to the preparation of cellulose from bamboo, esparto, wood pulp or other suitable material, I provide a digester *a* which may be of steel or other suitable material and of any usual or desired size and shape but preferably having its upper and lower portions *b* *c* tapered or conical, and to the lower part *c* of the digester I secure the delivery pipe *d* from the centrifugal pump *e* or other circulating device that may be employed, the draw-off pipe *f* for the liquor being situated in the upper part of the digester so that in contradistinction to known processes the 85 liquor is forced through the digester (which has been previously filled with the material to be treated) in an upward direction. The arrangement is such that the scum and other impurities are forced into the upper portion *b* of the digester by the rising liquor and the latter after leaving the digester is caused to pass through a separating or cleansing device or devices of suitable construction before passing to the heater *g* and thence to the suction pipe of the pump *e*. 90 95

In the construction illustrated the separating device comprises a vessel *h* of suitable size and shape, to the lower part of which is fitted the draw-off pipe *f* from the digester, this pipe communicating with a bell-mouthed or trumpet-shaped device *i* arranged within the outer vessel or container *h* and having its diameter expanding in the direction of flow so that the 100 105 velocity of flow will be diminished. The

effect of this arrangement is that the scum and impurities contained in the liquor will rise into the upper part of the separator vessel *h* above the bell-mouthed delivery device *i* while the liquor thus purified will flow over the lip or rim of the device *i* and fall by gravity into the lower part of the separator where I may arrange a strainer *k* through which the liquor will pass before going to the outlet pipe *l* leading to the heater *g* which may be of the tubular or other suitable form.

If desired or necessary I may arrange in the upper part of the digester a strainer *x* having relatively large apertures so that while not liable to become clogged will yet prevent the egress of large chips from the digester, and where necessary I may provide in conjunction with the separator *h* and preferably superposed thereon a gas separator such as *m* of the spiral screen or other known or desired type for the purpose of providing for the separation from the liquor of any gases that may accumulate in the digester during the operation.

Furthermore, I may if necessary provide in the interior of the digester and surrounding the inlet *n* a screen *o* of suitable form in order to keep the material clear of the inlet when the apparatus is standing, it being obvious that during operation the inlet will be automatically maintained free by the pressure of delivery of the liquor necessary to force the same through the column of pulp.

By suitable manipulation of the valves also the pressure of the liquor in the heater or in any other part of the apparatus may be artificially raised thus raising the boiling point and reducing the formation of bubbles in the heater tubes so that the clogging of the heater will be thus prevented or minimized.

It will be obvious that the apparatus is applicable also when an added substance or substances is or are introduced into the liquor such for example, when precipitating lime in the separator.

Having now described my invention, what I claim as new and desire to secure by Letters Patent is:—

1. Apparatus for use in the manufacture of cellulose, comprising a digester, a separator, a heater, and a pump, a feed pipe leading from said pump to the bottom of said digester, a draw-off pipe leading from the top of said digester to the bottom of said separator, means for carrying the liquid from said delivery pipe to the upper part of said separator, an outlet pipe leading from the bottom of said separator to the said heater, and a pipe leading from said heater to said pump, substantially as described.

2. Apparatus for use in the manufacture

of cellulose, comprising a digester provided with a strainer at the top and bottom thereof, a separator, a heater, and a pump, a feed pipe leading from said pump to the bottom of said digester, a draw-off pipe leading from the top of said digester to the bottom of said separator, a gas separator mounted above said first-named separator, an escape pipe for gas connected thereto, means for carrying the liquid from said delivery pipe to the upper part of said separator, an outlet pipe leading from the bottom of said separator to the said heater, and a pipe leading from said heater to said pump, substantially as described. 70 75 80

3. Apparatus for use in the manufacture of cellulose, comprising a digester, a plurality of separators, a heater, and a pump, a feed pipe leading from said pump to the bottom of said digester, a draw-off pipe 85 leading from the top of said digester to the bottom of said separators, means for carrying the liquid from said delivery pipe to the upper part of said separators, an outlet pipe leading from the bottom of said separators 90 to the said heater, and a pipe leading from said heater, to said pump, substantially as described.

4. Apparatus for use in the manufacture of cellulose, comprising a digester provided with a strainer at the top and bottom thereof, a plurality of separators, a heater, and a pump, a feed pipe leading from said pump to the bottom of said digester, a draw-off pipe leading from the top of said digester to the bottom of said separators, gas separators mounted above said first named separators, and escape pipes for gas connected thereto, means for carrying the liquid from said delivery pipe to the upper part of said separators, an outlet pipe leading from the bottom of said separators to the said heater, and a pipe leading from said heater to said pump, substantially as described. 95 100 105

5. Apparatus for use in the manufacture of cellulose, comprising a digester, a separator, a heater, and a pump, a feed pipe leading from said pump to the bottom of said digester, a draw-off pipe leading from the top of said digester to the bottom of said separator, a bell mouth inlet tube connected to said escape pipe for carrying the liquid from said delivery pipe to the upper part of said separator, an outlet pipe leading from the bottom of said separator to the said heater, and a pipe leading from said heater to said pump, substantially as described. 110 115 120

6. Apparatus for use in the manufacture of cellulose, comprising a digester provided with a strainer at the top and bottom thereof, a separator, a heater, and a pump, a feed pipe leading from said pump to the bottom of said digester, a draw-off pipe leading from the top of said digester to the bottom 125 130

of said separator, a gas separator mounted above said first-named separator, an escape pipe for gas connected thereto, a bell mouth inlet tube connected to said escape pipe for carrying the liquid from said delivery pipe to the upper part of said separator, an outlet pipe leading from the bottom of said

separator to the said heater, and a pipe leading from said heater to said pump, substantially as described.

10

In testimony whereof I have signed my name to this specification.

E. SCHAUFLERBERGER.
